UNITED STATES PATENT OFFICE

EARLE F. ALLEN, OF CAMBRIDGE, MASSACHUSETTS, ASSIGNOR TO ALLEN-DREW CO., OF CAMBRIDGE, MASSACHUSETTS, A CORPORATION OF MASSACHUSETTS

SHOW WINDOW

Application filed March 6, 1931. Serial No. 520,553.

This invention relates to display windows for the fronts of show rooms or the like, and has for its principal object the provision of a vertically movable window arranged to close a window opening in the front of a building or to be moved downwardly through a slot in the floor to a position beneath the floor level, so that vehicles such as automobiles may be driven from the street or sidewalk 10 through the window opening and onto the floor of the showroom. A further object is to provide automatic operating mechanism for quickly raising and lowering the window, this mechanism preferably being located beneath the window opening, for example in the basement of the building, so that the apparatus may be installed in previously erected buildings without dismantling the walls of the building or necessitating other material changes in its structure. Such disposition of the operating mechanism also affords ready access to the machinery and permits the employment of a rotatable shaft which preferably extends parallel to the window and is provided with elevating devices which react upon the window at opposite sides of its vertical center, and intermediate its ends, thereby insuring steady and uniform vertical movement of the window.

30 A recommended embodiment of the invention is illustrated in the accompanying drawings of a dropping window associated with a building front having a window opening leading from an interior show room to the exterior sidewalk. In said drawings:

Fig. 1 is a vertical section through the foundation of the building, showing the movable window and its operating mechanism in front elevation;

40 Fig. 2 is a central vertical section through the structure shown in Fig. 1;

Fig. 3 is a plan view of a motor driving unit and associated elements of the elevating mechanism;

45 Fig. 4 is a transverse section through one of the sides of the window frame, illustrating a guideway for the window; and

Fig. 5 is a side view of a rotatable drum forming part of the elevating apparatus.

50 In the particular embodiment chosen for

the purpose of illustration, the window 10 is arranged at the front wall 11 of a building provided with a show room having its floor 12 approximately at the level of the exterior sidewalk 13 and having a front window opening of substantial size communicating through a narrow vertical opening 14 in the floor or sill 12 with the basement of the building. The window opening is bordered at the sides by the building front 11 and at the top by a panel 15 forming part of the front 11. The window sash comprises top and bottom members 16 and 17 respectively, and side strips 18, the bottom strip 17 extending downwardly into the opening 14 when the window is fully closed as shown in the drawings, and the closed window accordingly has the appearance of a permanent installation. A flexible sealing strip 18' may be fastened to the sidewalk along the bottom strip 17 to prevent dirt or moisture from entering the opening 14.

Guideways 19 extend vertically along the opposite sides of the window opening and downwardly through the sill opening 14 into the basement, preferably terminating in a narrow recess or well 20 in the basement floor 21, thereby permitting the window to slide downwardly between the guides so that the upper sash strip 16 will lie within the opening 14, beneath the surface of the floor 12, when the window is in its lowermost position. The guides 19 may comprise angle irons formed to provide three parallel elongate channels including a central channel 22 and side grooves 23, as best shown in Fig. 4; and elongate metal strips 24, each having a central tongue 25 and parallel side tongues 26 received within the complementary channels, may be mounted on the outer edges of the sash strips 18. The central tongue 25 preferably has a sliding fit within its groove 22; whereas the side tongues 26 may be smaller than the grooves 23 to serve as auxiliary guides in case of necessity, and to protect the main guide members against damage from external contacts as well as from dirt and moisture.

The base strip 17 of the window preferably has several depending legs or brackets 27

braced by diagonal struts 28 and mounting pulleys or anti-friction members 29 at their lower ends, the pulleys being located at opposite sides of the center of the window. 5 Supporting cables 30, attached at one end to the foundation 31 as at 32, extend downwardly around said pulleys and thence upwardly to and around drums 33 splined to a horizontal shaft 34 journaled in brackets 35 mounted beneath the foundation 36 of the 10 floor 12. The opposite end of each cable 30 may be secured to its drum by passing said end through an opening in the side of the drum and clamping or knotting the projecting end as indicated at 37 of Fig. 5. Thus the 15 window may be raised or lowered by rotating the shaft 34 to decrease or increase the effective length of the cables 30, and it may be held stationary at any desired position by restraining rotation of the shaft. These 20 purposes may be attained by a variety of operative mechanisms in accordance with common practice.

It will be observed that the shaft 34 is substantially as long as the window and extends parallel thereto beneath the window opening, and that the drums 33 are mounted upon the shaft at opposite sides of the vertical center of the window in operative relationship to the 25 pulleys 29. Hence, the operative force exerted upon the window by winding or unwinding the cables 30 upon the drums 33 is applied uniformly along the entire length of the balanced window and at points intermediate its ends, thereby relieving excessive strain upon the operating mechanism and tending to prevent binding between the side strips 18 and the guideways 19. It is apparent that one or more pairs of working cables, 30 pulleys and drums may be provided, depending upon the length and weight of the window; the two pairs herein illustrated being shown by way of example only.

In the illustrated embodiment of the invention, the window is normally urged toward and supported in its elevated or closed position by means of a counterweight 38 which is vertically movable in a skeleton cage 39 mounted on the basement floor 21. A counterweight cable 40, fixed at one end 41 to the foundation 26, passes under a pulley 42 on the counterweight and thence upwardly over a drum 43 mounted on the shaft 34, the opposite end of the cable being attached to said drum in the manner aforesaid. The inertia of the counterweight is preferably sufficient to overbalance the weight of the window, thereby to relieve strain on the operating mechanism when the window is closed.

60 The operating mechanism may include an electric motor unit mounted upon a suitable support 44 adjacent the shaft 34 and comprising a reversible motor 45 having a shaft 46 passing through electrically-operative braking mechanism 47 to a gear box 48; comple-

mental worm and spur gears in the gear box operating a driving shaft 49 extending parallel to the driven shaft 34; and mutually engaging gears 50 and 51 mounted on the respective shafts 49 and 34. The precise construction and arrangement of the elements of the motor unit and the electrical circuits associated therewith, which may include a switch box 52, a three button control switch 53 and an automatic cut-out 54 controlled by 75 the driving shaft 49, form no part of the present invention.

When the window 10 is closed, operation of the motor rotates shaft 34 and its drums 33 and 43, pulling up the counterweight by shortening cable 40 and allowing the window gradually to slide downwardly upon its released supporting cables 30 until the motor is stopped by pressing one of the buttons of switch 53 or by the automatic cut-out 54 when the window reaches its lowermost position. In its lowered position, the upper sash strip 16 of the window is beneath the floor level 12, as aforesaid, so that an automobile may be driven into or out of the show room 90 through the window opening. Upon reversing the motor, the window is slowly elevated and the counterweight is permitted to descend by relaxation of its cable.

By the simple and efficient arrangement above described, a display window may be moved upwardly or downwardly in a vertical direction to close or open a large sized opening in the front of a building and allow the entrance or exit of vehicles to or from a show room behind the opening. The operating apparatus may be easily installed in an underlying basement or other enclosure where it occupies a minimum of space and is readily accessible for adjustment or repair. Owing to the disposition of the automatic mechanism beneath the window opening and the preferred arrangement of the operating devices, it is not necessary that the building walls be unusually thick to accommodate pulleys, cables or other mechanical elements; yet the working parts are all concealed from the view of persons passing the window or entering the show room. Hence, the entire apparatus may be readily installed in an existing building without excessive reconstruction or remodeling of its walls or foundations, and the closed window presents substantially no visible indication that it is not a permanent and fixed installation. The window affords clear inspection of the cars displayed in the floor of the show room. The operation of the window is smooth and uninterrupted, and its movement may be controlled automatically as by means of a remotely located switch.

It should be understood that the present disclosure is for the purpose of illustration only and that this invention includes all modi- 130

fications and equivalents which fall within the scope of the appended claims.

I claim:

- 5 1. In association with a window movable from open to closed position through an opening in a sill, window operating mechanism located beneath the sill and comprising a horizontal shaft substantially as long as the window and extending parallel thereto, drums fixed to said shaft, pulleys secured to the bottom of said window, window elevating cables attached at one end to the individual drums and passing around said pulleys with their opposite ends fixed at a point above the lower edge of the fully elevated window, said pulleys and drums being arranged in pairs disposed on opposite sides of the vertical center line of the window, and means for rotating the shaft to raise or lower the window.
- 10 2. In association with a window movable from open to closed position through an opening in the sill, window operating mechanism located beneath the sill and comprising a horizontal shaft extending parallel to said window, anti-friction members secured to the lower end of said window, window elevating cables adapted to be wound about said shaft for raising said window, said cables extending transversely beneath and engaging said anti-friction members on said window on opposite sides of its vertical center, one end of said cables being secured to a point above the lower edge of the fully elevated window, and means for rotating said shaft in either direction to raise or lower said window.
- 15 3. In association with a window movable from open to closed position through an opening in the sill, window operating mechanism located beneath the sill and comprising a horizontal shaft extending parallel to said window, anti-friction members secured to the lower end of said window on opposite sides of its vertical center, cables adapted to be wound about said shaft for raising said window, said cables extending transversely beneath and slidably engaging said anti-friction members on the lower end of said window, the opposite end of each cable being fixed to a point above the lower edge of the fully elevated window, and means disposed beneath said sill for rotating said shaft in either direction to raise or lower said window.
- 20 4. In association with a window movable from open to closed position through an opening in the sill, window operating mechanism located beneath the sill and comprising a horizontal shaft extending parallel to said window, pulleys secured to the bottom of said window on opposite sides of its vertical center, drums on said shaft, window elevating cables attached at one end to the individual drums and passing beneath the lower edge of

the window and engaging said pulleys, the opposite end of the cables being fixed to a point above the lower edge of the fully elevated window, and means for rotating the shaft to raise or lower the window.

Signed by me at Boston, Massachusetts, this 5th day of February, 1931.

EARLE F. ALLEN.
